United States Patent Office.

WILLIAM F. SHAW, OF BOSTON, MASSACHUSETTS.

Letters Patent No. 71,333, dated November 26, 1867.

IMPROVEMENT IN LAMP-SHADES.

The Schedule referred to in these Letters Patent and making part of the same.

TO ALL WHOM IT MAY CONCERN:

Be it known that I, WILLIAM F. SHAW, of Boston, county of Suffolk, and Commonwealth of Massachusetts, have invented a new and useful Improved Dome-Shade; and I hereby declare the following to be a full, clear, and exact description thereof, which will enable others to make and use my invention, reference being had to the accompanying drawings, forming part of this specification, in which is exhibited a side elevation of my improved shade, with its holder; also, a bottom or top edge view of the holder.

A shows the side elevation, B the top or bottom edge view of the holder. Similar forms of shades have before this been manufactured of brass and other materials, the peculiar character of the material employed rendering the manner of manufacture feasible. The dome or semi-spheroidal form is imparted by hammering or being "spun up" in a lathe. But this is, in comparison with my process of manufacture, expensive, involving a considerably higher cost in the completed article.

My improved shade is made, in the first place, from one piece of tin, struck up in a press. The material employed and mode of manufacture greatly lessen the cost. Moreover, tin is a metal that cannot be used for this purpose, and be manufactured into the form shown in the drawings, or similar forms, by being spun up, inasmuch as from its nature it will not admit of such a method to sufficient depth to manufacture an article like this. B is the holder or ring that embraces the burner or chimney to sustain the shade. It is corrugated, and may be made either of flat metal, as illustrated in the drawing, or of wire. When thus made of flat metal, and corrugated, it easily adjusts itself to varying sizes of burners or chimneys, and maintains the shade in a secure and upright position, sufficient to prevent its inclination or striking against chimneys, &c., over which it may be placed. 1 2 3 show the rods or outrunners uniting the adjustable holder to the dome, as common.

What I claim as my invention, and desire to secure by Letters Patent, is—

1. The corrugated adjustable holder B, as and for the purposes specified.
2. The improved dome-shade, when manufactured of the material and in the manner herein set forth and for the specified purposes.

W. F. SHAW.
